UNITED STATES PATENT OFFICE.

ELWIN H. ROONEY, OF WHITINSVILLE, MASSACHUSETTS, ASSIGNOR TO THE WHITIN MACHINE WORKS, OF WHITINSVILLE, MASSACHUSETTS, A CORPORATION OF MASSACHUSETTS.

COMBER FEED-ROLL MOTION.

1,176,318.

Specification of Letters Patent. Patented Mar. 21, 1916.

Application filed February 5, 1912. Serial No. 675,468.

To all whom it may concern:

Be it known that I, ELWIN H. ROONEY, a citizen of the United States, residing in Whitinsville, Massachusetts, have invented 5 the following-described new and useful Improvements in Comber Feed-Roll Motions.

The invention relates more particularly to the feed motion of Heilmann type combers and its object is to improve the extent and character of the overlap and generally to promote the efficiency of the 10 comber and also to simplify the drive mechanism of the feed rolls whereby the first cost and also the cost of upkeep and the 15 care of such mechanism is reduced.

The invention consists in the construction exemplified by the structure shown in the drawings forming part herein and detailed in the following description:

20 Figure 1 of the drawings is a partial top plan of the driving mechanism of a Heilmann comber with certain well understood parts removed. Fig. 2 is an enlarged end elevation of the feed roll gearing shown in 25 Fig. 1. Fig. 3 is a rear elevation of the same gearing on enlarged scale. Fig. 4 is a detail. Fig. 5 is a sectional view on line 5-5 of Fig. 2 and Fig. 6 is a cross-section of one of the combing heads of a Heilmann 30 tyre comber.

Referring first to Figs. 1 and 6, the comber therein illustrated comprises the usual series of frame uprights 1, which divide and support the several combing 35 heads of the machine and the uprights 2 and 3 which form the support of the various parts of the driving mechanism. The roll of lap to be combed is carried upon the pair of lap roll rollers 4, shown in Fig. 1, and 40 by them passed over an apron 5, part of which only is shown in Fig. 6, into the nip of the feed rolls 6 and 7, by which the lap is supplied to the nipper mechanism. The upper feed roll 6 is held against the lower 45 roll 7 by a pair of arms, as indicated and which are under spring pressure (not shown). The lower roll 7 is mounted or formed as usual on a continuous shaft 8 common to all the combing heads of the 50 machine and extending therefrom into the space between the uprights 1 and 3, which space and the uprights therein form the drive head of the comber. The nipper mechanism comprises a pair of alternately opening and closing jaws 9 and 10 actuated by

the connections shown, which, when open, allow the lap to move therethrough to a desired extent and when closed, nip and hold the lap while the half lap 11 on the combing cylinder acts upon its projecting end. 60 After this end or tuft has been thus combed it is pressed by the detaching segment 12 against the lower side of the detaching roll 13 and thereby separated or detached from the body of the lap and passed forwardly 65 into the piecing rolls 14 and 15, where it is overlapped or pieced on the tail end of the previously combed and detached tuft in the usual way and thence passes out through the pan 16 as a continuous sliver, as will be 70 well understood.

The combing cylinder is mounted on a comb shaft 17, which like the feed roll shaft 8 is also common to all the combing heads, 75 as will be understood, and extends from the latter into the drive head above referred to where it is journaled in each of the frame uprights and driven by its index wheel 18 from the drive pinion 19 on a primary drive shaft 20, 17^a being an ordinary shaft coupling. It will, of course, be understood by those skilled in this art that the drive head of the comber includes many other parts which may be also driven by the same drive 80 shaft for operating the nipping and piecing mechanism as well as the scavenging mechanism. For sake of clearness in the drawings these are omitted as not essential to an 85 understanding of this invention.

The continuous feed roll shaft 8 terminates in a journal bearing in the same frame upright 2 that forms the intermediate drive head support for the comb shaft 17 and bears a worm wheel 21 fast thereon on the side of the said upright which is nearest to 90 the combing heads. On the opposite side of the upright the comb shaft is supplied with a bevel pinion 22 and between the worm wheel and pinion is a train of gearing 95 through which the comb shaft drives the feed roll shaft. This train is of the constant motion type, that is to say, consists wholly of spur or worm teeth or both together, arranged to impart the motion of the comb shaft to the feed roll shaft with 100 no change except as to the speed ratio. As the comb shaft rotates continuously and at a constant rate, it follows that the feed roll shaft will also rotate at a constant rate and 105 continuously by reason of the use of the type 110

of gearing train referred to. The feed roll shaft, thus constantly and continuously rotated, is connected at its opposite end with the gearing and shafting shown in dotted lines and marked 23 in Fig. 1 whereby it drives the lap roll rollers above referred to so that the lap unwinding from the lap roll thus receives a continuous motion toward the jaws of the nipper mechanism, such motion taking place when those jaws are open as well as when they are closed but being a relatively slow motion so that the lap will not unduly accumulate behind the closed jaws. The accumulation behind the closed 10 nippers will ordinarily not take place to such extent as to interfere with the arrangement of the fibers as by producing a fold in the lap, but appears merely as a slight fullness in the lap between the feed-rolls 15 and the nippers and is readily eliminated when, on the opening of the nippers the tuft is drawn forward in the detaching operation.

The train of gearing above referred to 20 comprises in its organization a change-speed mechanism by which the rate of the feed roll motion may be altered. More specifically the said train consists of a bevel pinion 24 which meshes with the bevel pinion 22 25 and is fast on a short shaft 25, which latter shaft carries a small pinion 25' in mesh with a larger idler spur gear 27, the latter being mounted on an adjustable stud 28. Through this idler the comb shaft motion is imparted 30 to a pinion 29 on a worm shaft 30, the worm 31 of which meshes with and drives the worm wheel 21 above referred to. The worm shaft 30 is disposed on the combing head side of the frame upright 2, being journaled in 35 a bracket-bearing 32 which is separately shown in Fig. 4 and which is adjustably secured to the side of the upright by means of a bolt 33 and a suitable oblong slot. The adjustment of the bracket 32 accommodates 40 the adjustment of the position of the feed roll shaft, the bearing 34 of which is adjustably bolted to the inclined upper edge of the frame upright. The shaft 25 and the stud 28 of the idler gear are carried on a 45 separate bracket secured to the opposite side of the said upright and preferably by the same bolt 33 which for this purpose extends through the head 2^a of that upright. The shank portion 35 of the latter bracket is car-

ried on a recessed and slotted slide block 36 fitting the head 2^a of the upright, as well as the shank, and clamped between these two members so as to hold the latter rigidly in an adjusted and proper position. The ear 37 at the lower end of the shank forms the 60 journal seat for the shaft 25 and a web 38 perpendicular to the shank and frame-upright, between the latter and the ear forms the support for the idler gear, being provided with a slot 39 in which the stud shaft 65 28 of said idler is adjustably secured. Such slot 39 is preferably arcuate and concentric with the axis of the shaft 25 and where it approaches the shaft 25 the latter is fenestrated as shown at 40 to provide access to 70 the nut of the stud 28 in any position that such stud may occupy in the arcuate slot. The pinion 29 is a change gear, being attached to its worm shaft so that it can be readily removed and replaced by another 75 change gear of different size, the axis of the idler 27 being shifted accordingly so that any desired rate of feed roll motion, *i.e.*, any extent of lap feed per combing nip of the machine can thus be obtained.

I claim:

1. In a Heilman comber, the combination of the lap feed rolls and including a feed roll shaft, the nipper and piecing mechanisms and the combing cylinder shaft, of means for advancing a continuous lap with a unidirectional movement to said feed rolls, and a train of continuous motion gearing for driving the feed roll shaft and adapted to impart continuous motion to the feed rolls 90 without severing the said lap.

2. A Heilman comber comprising nipper mechanism including alternately opening and closing jaws, and combing and piecing means co-operating therewith in combination 95 with lap-supplying means in rear of said jaws comprising one or more lap-advancing members each rotating only in a forward direction, and the advancing member which is immediately in rear of such jaws having 100 a continuous forward motion.

In testimony whereof, I have signed this specification in the presence of two witnesses.

ELWIN H. ROONEY.
